UNITED STATES PATENT OFFICE.

MATH SMITH, OF DAVENPORT, IOWA.

APPARATUS FOR TREATING FABRICS.

1,209,773.

Specification of Letters Patent. Patented Dec. 26, 1916.

Application filed March 31, 1916. Serial No. 87,890.

To all whom it may concern:

Be it known that I, MATH SMITH, a citizen of the United States, residing at Davenport, in the county of Scott and State of Iowa, have invented certain new and useful Improvements in Apparatus for Treating Fabrics, of which the following is a specification.

My invention relates to improvements in apparatus for treating fabrics and has especial reference to devices of this character for raising the nap on velvet, or the like, for smoothing wrinkles out of such or other material and for sponging, shrinking and "steaming" cloth and other such fabrics.

One of the objects of my invention is to provide a neat machine, simple in construction and efficient in operation, adapted to be cheaply produced and which will thoroughly, completely and evenly distribute moisture and heat throughout the fabric structure, whereby to impart that desirable new appearance and quality to the fabric by raising the nap, removing wrinkles and creases and furthermore by contracting its dimensions by the process of shrinking.

Other and further objects of my invention will become readily apparent, to persons skilled in the art, from a consideration of the following description when taken in conjunction with the drawings, wherein:

Figure 1 is a side elevation of my improved device with parts broken away and shown in section. Fig. 2 is a section taken on line 2—2 of Fig. 1. Fig. 3 is an end view showing parts in section. Fig. 4 is a bottom view of the top or cover showing parts broken away. Fig. 5 is a transverse view through the top or cover and part of the vapor generator. Fig. 6 is a section taken on line 6—6 of Fig. 5.

In all the views the same reference characters are employed to indicate similar parts.

In the accompanying drawings I have illustrated a preferred form of my invention, which consists of three separable, major portions comprising the base frame 10, the vapor or steam generator 11 and the top or cover 12.

The base portion is provided with two end frames 13 and 14, each having two legs

15—15, upon which the device is supported. To each of the frames is secured a bracket 16, as by rivets or bolts 17, upon which to support the gas burner 18. A strap 19 overlies the gas burner, or pipe 18, and is secured to the upper surface of each of the brackets 16 by screws or rivets to hold the gas burner in proper position. The burner pipe 18 is provided with a series of spaced-apart burners 20, let into the upper surface of the burner pipe and having slots 21, angularly disposed, so as to provide substantially a continuous flame from one end to the other of the pipe, so as to uniformly heat the bottom 22 of the vapor generator or water container 11. The frames 13 and 14 are connected together by a longitudinally-extending, perforated strip 23, as at 24. This strip is bent at an angle, as at 23', to form a base upon which the generator 11 rests. Another strip 25, which is preferably an inturned part of each of the frames 13 and 14, and which are in substantially the same plane as the strips 23', join the latter 75 oppositely disposed parallel strips, being connected thereto, as by rivets, as at 26. Side wings 27, constituting flame guards extend laterally and downwardly from the upper edge of the supporting structure and are 80 inturned at their ends, as at 28, and connected at their ends to the respective frames 13 and 14, as at 29. These portions provide shields for protection of the fabric, or cloth 30 being treated, from direct contact with 85 the flame issuing from the burner 18. To the inside surface of the guards 27 is secured a lining 31 of asbestos, or the like, to prevent the upper metal surface of the guards from being heated to such a dangerous degree as 90 to scorch or injure the fabric.

The steam or vapor generator, or water receptacle 11, is generally rectangular in form, tapering slightly from the bottom to the top; the top being slightly convexo-concave or 95 raised near its transverse center provided with a longitudinally extending trough-like depression 32 containing in its bottom wall a series of spaced apart, angularly disposed slots 33, through which the steam or vapor 100 is to pass out of the receptacle 11, into the trough in a substantially continuous longi-

tudinally extending stream through or into contact with the cloth 30 that is being treated, by this means every particle of the overlying fabric is evenly subjected to the effect 5 of the heat and steam or vapor. Surrounding the part 32 is another troughlike structure or water trap 34, somewhat larger than the structure 32 leaving a substantial space therebetween and provided in its side walls 10 with a series of steam or vapor admitting perforations 35. These perforations are made near the top of the side walls of the structure 34 thus forming a trap in the structure 34 through which the steam passes, in 15 its exit from the generator through the slots 33 and 35, into the longitudinally extending depression or trough immediately below the cloth 30. At each end of the structure 34, and at one or two other intermediate points, 20 a small perforation 36 is made in the bottom wall to permit the entrapped water or condensed vapor that may be caught in the structure 34, to entrain back into the reservoir or generator. The area of the perforations 36 is so small, compared to the perforations 35 that little if any steam or vapor will 25 pass through the former perforations, most of it going through the perforations 35 and out through the perforations 33, the water 30 being returned through the perforations 36.

I prefer to cover the longitudinally extending depression or slot 32, in the top wall of the generator 11, when the cloth 30 is being treated, for the purpose of confining the 35 vapor directly to the cloth and for holding the cloth intimately in contact with the upper surface of the trough, and with this end in view I provide the top 12, consisting of longitudinally-extending angularly disposed 40 top plates 37 and 38, which as a matter of fact is a single piece bent at the apex 39, and extending downwardly and laterally, each being under-turned at its longitudinal edge, as at 40, to provide a roll or conduit 41. 45 The under side of the plates 37 and 38 contain a sheet of moisture-absorbing material 42, such as a strip of felt, having its longitudinal edges terminating over the conduits 41—41, so that when this fabric or absorbing 50 material becomes super-saturated with moisture it will drip off at its longitudinal edges into the conduits 41—41 and be entrained out through the apertures 43 at each end of the conduits. End plates 44 connect the 55 plates 37 and 38, having their transverse ends 45 bent at right angles so as to encompass the sides of the generator 11 to guidingly hold the top structure in place upon the generator. The plates 44, furthermore, 60 have inturned fingers 46 which rest upon the top surface of the generator 11 and support the top structure a proper distance above the trough 32. A zigzag wire 47 extends transversely under the absorbent pad 42 to

hold it in place, having the ends 48 of each 65 of its loops tucked under the salient edges 40 of the plates 37 and 38 to hold the pad in place. The wire structure 47 may be easily removed for supplying a new pad.

Each of the end plates 44 is provided with 70 an upwardly extending latch member 49 to receive rod ends 50. A strip of flannel, or other similar yielding material 51 surrounds each of the rods 50 and extends over and between the conduits 40—40, and yieldingly 75 rests upon the upper edge of the depression or trough 32 made in the top wall of the generator. The rods 50 are held parallel and in place by the brackets 49—49 and by means of a centrally disposed clip 52. The 80 clip 52 has its ends upturned into hooks 53 which partly surround the rods 50—50 to hold them spaced apart the proper distance to maintain the rods parallel, the cloth 51 being cut away, as at 55, for exposing the 85 rods, and to the center of the clip 52 is secured a knob or handle 54, by means of which the top, as a whole, may be lifted from its resting place upon the generator. By this means the cloth 51 may be held in 90 its place and a new cloth may be substituted by disengaging the rods from the end brackets and the central clip, a new cloth may be put on the rods and the cloth and rods replaced.

95 Located at one end of the generator 11 is a water reservoir 60 consisting, preferably, of a glass jar, such as a Mason jar, having a screw threaded top 61 provided with an orifice 62, supported in a tray 63 which communicates with the interior of the reservoir, as by means of a pipe 64. A tray 63 is secured in place by braces 65 which are fixed to the under side of the tray and to the sides of the generator. The jar 60 is filled with 100 water and inverted and placed with its neck in the tray 63, and automatically maintains the water level in the generator 11 at a constant height, by a principle well understood.

105 The operation of the device is as follows:— 110 The top 12 is removed and the cloth strip of velvet, or the like, is grasped by its ends in the hands, one end in each hand, and after the top has been replaced, and with considerable downward pressure the strip is slowly 115 drawn back and forth transversely across the rounded top of the generator. Hot, dry steam or vapor will pass through the oblique openings 33 into the longitudinally extending trough 32 in the top wall and into and 120 through the fabric. The superposed cloth 51 will hold the steam and heat within that portion of the cloth 30, that is at the time over the trough being treated, and will prevent condensation of the moisture, or steam, 125 and escape of the heat, thus maintaining the cloth so treated a longer time under the influence of the heat and moisture proceeding

from the device. The device is especially well adapted for milliners use and when velvet is being treated the effect of the heat and evenly distributed moisture will raise 5 the nap and cause the velvet to assume substantially the same general condition and appearance that it is given when new.

The arrangement of the device is such, due largely to the effect of the trough, that the 10 moisture and heat will be so evenly distributed as not to produce spots, stains or blotches in the fabric to cause undesirable discoloration or unequal shrinkage.

While I have herein shown a single embodiment of my invention for the purpose of clear disclosure, it is evident that considerable variation may be made in the general arrangement and disposition of the parts within the scope of the appended claims.

20 Having described my invention, what I claim is:—

1. A device of the character described, comprising a generator, provided with an arched top wall having a trough-like depression extending substantially its full 25 length and into said generator and perforated in its bottom wall for egress of steam, or vapor, into said trough, whereby to evenly distribute it unobstructedly to the 30 superposed fabric under treatment; a surrounding trough-like trap, within said generator, having its side walls perforated for communication with the generator and its bottom wall having relatively small perforations whereby to entrain the liquid of 35 condensation, and means for heating the liquid within the generator.

2. A device of the character described, comprising a generator, provided with an 40 arched top wall having a trough-like depression extending substantially its full length and into said generator and perforated in its bottom wall for egress of steam, or vapor, into said trough, whereby to evenly 45 distribute it unobstructedly to the superposed fabric under treatment; a superposed cover for overlying said fabric under treatment; an absorbent, yielding sheet normally covering said trough, carried by said cover, 50 and a guide for holding the cover on said generator and spacing it thereabove.

3. A device of the character described, comprising a burner-supporting frame structure; a separable steam generator, removably 55 mounted thereon, said generator having a continuous elongated slot formed in its top wall; a water trap extending under said slot, within said generator, having openings to entrain water into said generator 60 to and to permit only steam or vapor to escape through said elongated slot.

4. A device of the character described, comprising a burner-supporting frame structure; a separable steam generator, remov-

ably mounted thereon, said generator having a continuous elongated slot formed in its top wall; a water trap extending under said slot, within said generator, having openings to entrain water into said generator and other openings to permit steam, or vapor to escape through said elongated slot and means to automatically maintain water level in said generator below said trap.

5. A device of the character described comprising a burner-supporting frame structure; a separable generator, removably mounted thereon, said generator having a continuous elongated slot formed in its top wall; a water trap extending under said slot within said generator, having openings to entrain water into said generator and other openings to permit steam or vapor to escape from said elongated slot into contact with the cloth being treated; means to automatically maintain water level in said generator, below said trap and a removable top or cover having a yielding moisture-absorbing fabric normally covering said slot and to overlie the cloth being treated by use of the device.

6. A device of the character described, comprising a burner structure surmounted by a water containing steam generator, said generator having a transversely arched top provided with a channel-shaped depression having a plurality of diagonally disposed steam orifices in the bottom thereof, and a removable spaced-apart cover provided with a yielding fabric normally overlying and covering the mouth of said channel.

7. A device of the character described, comprising a heat generating structure; a steam or vapor generating structure separably mounted thereon and provided with a channel shaped depression extending longitudinally of its top wall and having steam or vapor openings spaced apart in the bottom of said depression; a trap within said water compartment surrounding said channel-shaped depression throughout its length, and a water reservoir rising above and communicating with said steam or vapor generator to automatically maintain water level therein.

8. A device of the character described, comprising a steam or vapor generator, having an arch-shaped top with a depression in the wall of the said top at the apex of the arch, said depression provided with steam openings; a removable spaced-apart arch-shaped top structure, having the apex of its arch substantially in the same vertical plane as that of the generator structure and having its terminal side edges inturned to form conduits; a moisture absorbing pad underlying the members of the arch structure, terminating in said conduits and a yielding cloth extending

between said conduits and overlying the depression in the top of said generator, between which and said depression the cloth or fabric to be treated is to be contained, and means for heating the contents of the generator.

In testimony whereof I hereunto set my

Copies of this patent may be obtained for five cents each, by addressing the "Commissioner of Patents, Washington, D. C."

hand in the presence of two subscribing witnesses.

MATH SMITH.
